[57] CLAIM

The ornamental design for a conversion van interior, as shown and described.

DESCRIPTION

FIG. 1 is a fragmentary perspective view of the left side of a conversion van interior showing our new design;

FIG. 2 is a fragmentary perspective view of the right side of a conversion van interior; and,

FIG. 3 is a fragmentary perspective view of the ceiling surfaces of the conversion van interior.

The surfaces or portions of the article not shown in the drawing or described in the specification or shown in dashed-line form no part of the design.

The broken line showings of interior and exterior portions of a van are for illustrative purposes only and form no part of the claimed design.
